UNITED STATES PATENT OFFICE.

ERNEST H. SCHMIDT, OF CLEVELAND, OHIO, ASSIGNOR TO THE NATIONAL MALLEABLE CASTINGS COMPANY, OF CLEVELAND, OHIO, A CORPORATION OF OHIO.

RADIAL-DRAFT GEAR.

971,930.

Specification of Letters Patent.

Patented Oct. 4, 1910.

Application filed December 3, 1909. Serial No. 531,124.

To all whom it may concern:

Be it known that I, ERNEST H. SCHMIDT, of Cleveland, Cuyahoga county, Ohio, have invented a new and useful Improvement in 5 Radial-Draft Gears, of which the following is a full, clear, and exact description, reference being had to the accompanying drawings, forming part of this specification, in which—

10 Figure 1 is a plan view of a portion of a car structure having a draft gear applied thereto embodying my invention; Fig. 2 is a view of the same partly in vertical section and partly in side elevation; Fig. 3 is a detail sectional view showing one form of connection with the car truck; Fig. 4 is a section on the line IV—IV of Fig. 3; Fig. 5 is a perspective view of one of the plungers; Fig. 6 is a longitudinal sectional view 20 showing a modified form of connection with the car truck; and Fig. 7 is a view on the line VII—VII of Fig. 6.

My invention has relation to radial draft gears, and is designed to provide means of 25 simple and efficient character whereby cars which are already equipped with radially swinging couplers may be provided with means for guiding the couplers to substantially the center of the track.

30 The precise nature of my invention will be best understood by reference to the accompanying drawings, which will now be described, it being premised, however, that various changes may be made in the details 35 of construction and arrangement of the several parts without departing from the spirit and scope of my invention as defined in the appended claims.

In these drawings, the numeral 2 designates 40 a radially swinging arm, which is pivotally connected to the under frame of the car structure by the pin 3.

45 4 is a tie rod, which connects the pin 3 to the king bolt or center pin 5, for the purpose of giving additional strength in pulling. As the points 3 and 5 are fixed points on the car body, the tie rod 4 has no radial movement.

50 Rigidly secured to the under side of the radially swinging arm 2, near its forward end, is a barrel-shaped casting or stop member 6 through the center of the rounded portion of which passes the coupler shank extension 7 of the coupler 8. Springs 9 and 55 10 surround the coupler shank extension at

opposite sides of the member 6, the draft spring 9 seating at its forward end against a follower 11, and at its rear end against the member 6. The spring 10 seats at its forward end against the rear side of the 60 member 6 and at its rear end against a follower 12, which is secured against rearward movement by a nut 13, or other suitable means. The spring 9 acts as a buffer and the spring 10 as the draft spring. 65

The coupler 8 may be of any suitable type, preferably of the M. C. B. type, and having suitable operating mechanism 14, which forms no part of the present invention. In fact, all the parts thus far described are 70 known in the art, and are herein shown and described only in order that the operation and purpose of my invention may be more clearly understood.

This invention consists in providing 75 means adapted to engage the member 6 for the purpose of guiding the coupler substantially to the center of the track in passing around curves.

15 designates a bracket, which is rigidly 80 secured to the channel bar member 16 of the truck frame, and has an upwardly extending arm provided with strengthening ribs 15^a and 15^b. The upper end of the bracket arm forms a semi-cylindrical socket 15^c. The 85 ribs 15^a are provided with rectangular openings 15^d for engagement with spring plungers 17 in the manner best shown in Fig. 4. One of these plungers is shown in detail in Fig. 5, and consists of a rectangular portion 90 adapted for insertion in one of the apertures 15^d. Its opposite end portion may be made circular and provided with a flange 18 to form a bearing for a centering spring 19. This spring seats between the two plungers 95 in the manner clearly shown in Fig. 4 and partially within the socket 15^c of the bracket, the latter acting to hold the spring centrally in position.

20 designates a spring compressor having 100 a semi-cylindrical upper portion 20^a adapted to fit the lower portion of the barrel-shaped member 6 and to be rigidly secured thereto. The lower portion of the compressor 20 is formed with the two jaws 20^b, which embrace the ends of the plungers 17. These plungers are inserted in position in the rectangular apertures 15^d, and the centering spring 19 is then compressed and placed between the plungers where it acts to press 110

them outwardly against the inner faces of the jaws 20^b. As the truck frames pivot in following track curves, the bracket 15 causes the plungers to bear against one jaw or the other of the spring compressor 20. The latter, through its connection with the member 6, forces the radius arm 2 to rotate about the center 3, and thereby carry the coupler to substantially the center of the track. The centering spring 19 affords an elastic contact for the plungers against the jaws 20^b so that if the coupler is forced to either the right or left of the position to which it is normally guided by the connections, the spring will yield either to the right or left; and when the force has ceased, will return the coupler to its normal position again.

The form of the invention above described is particularly applicable to motor truck 20 cars. For trailer cars having higher truck frames I may employ a form of bracket such as illustrated at 21 in Figs. 6 and 7, in which the extending arm instead of being upwardly directed is substantially horizontal. The 25 construction shown in Figs. 6 and 7 is otherwise similar to that first described.

My invention provides means of simple and effective character whereby cars which are equipped with radially swinging 30 couplers may be provided with means for guiding the couplers to substantially the center of the track.

It will be obvious that various changes 35 may be made in the details of construction and arrangement of the parts. Thus, my invention is not limited to the particular form of swinging arm, coupler, and draft rigging illustrated, but may be used in connection with other forms of radially swinging 40 couplers; and the form and arrangement of the parts constituting my invention may obviously be changed in various details.

What I claim is:

1. The combination with a radially swinging 45 arm, a coupler, and a draft rigging carried by said arm, of a guiding connection for

the coupler consisting of a member secured to the truck frame, a jaw member carried by the radially swinging arm, and a spring device carried by the first named member and 50 adapted to engage the jaw member upon pivotal movement of the truck frame in either direction; substantially as described.

2. The combination with a radially swinging arm having a depending portion, a 55 coupler shank and draft rigging supported by said depending portion, a bracket secured to the truck frame, a pair of oppositely acting spring plungers carried by said bracket, and another member secured to the said depending portion and engaging said plungers; substantially as described.

3. In a draft gear, a radially swinging arm having a depending portion near its forward end, a coupler having a shank extension passing through said portion, a member secured to said portion and having opposite jaws, a bracket secured to the truck frame, a pair of oppositely acting plungers seated in said bracket, and engaging the said 70 jaws, and a centering spring between said plungers; substantially as described.

4. In a draft gear, the combination with a radially swinging arm and a coupler carried by said arm, of means for guiding said 75 coupler radially, comprising a jaw member carried by said arm, a member secured to the truck frame and having a socket portion, a pair of oppositely acting plungers seated in the last named member and arranged to 80 engage the jaws of the jaw member, and a spring seated in said socket portion and engaging both plungers to force them outwardly into engagement with said jaws; substantially as described.

In testimony whereof, I have hereunto set my hand.

ERNEST H. SCHMIDT.
